(57) **CLAIM**

The ornamental design for a charger for rechargeable batteries for diagnostic instruments, as shown and described.

DESCRIPTION

FIG. 1 shows a perspective view of the charger for rechargeable batteries for diagnostic instruments;
FIG. 2 shows a front elevation view of the charger for rechargeable batteries for diagnostic instruments;
FIG. 3 shows a right side elevation of the charger for rechargeable batteries for diagnostic instruments;
FIG. 4 shows a left side elevation of the charger for rechargeable batteries for diagnostic instruments;
FIG. 5 shows a rear elevation of the charger for rechargeable batteries for diagnostic instruments;
FIG. 6 shows a top plan view of the charger for rechargeable batteries for diagnostic instruments; and,
FIG. 7 shows a bottom plan view of the charger for rechargeable batteries for diagnostic instruments.
